PIPE GRIPPING TOOL

Lawrence E. Dunlap, Carrollton, Ohio

Application November 8, 1949, Serial No. 126,222

5 Claims. (Cl. 294—92)

1

The invention relates generally to means for clamping or gripping an elongated article intermediate its ends for raising and lowering the same by means of a crane or hoist, and more particularly to a pipe gripping tool which is suitable for raising and lowering lengths of pipe in a substantially upright position, as in a well.

Certain prior pipe gripping tools have included slings or clamps which are satisfactory for gripping a pipe midway of its ends to lift it in a substantially horizontal position, but these devices have not been satisfactory for raising or lowering a pipe in upright position because of the tendency of the pipe to slip. Other prior pipe gripping devices which have securely gripped the pipe are difficult to fasten or apply, frequently requiring tools, and are either complicated and expensive to manufacture, or heavy and awkward to manipulate, or both.

It is an object of the present invention to provide a novel pipe gripping tool for tightly gripping a length of pipe intermediate its ends to securely hold the same in substantially upright position.

Another object is to provide a novel pipe gripping tool which is quickly and easily fastened or unfastened without requiring tools.

Another object is to provide a novel pipe gripping tool which utilizes a length of ordinary chain to securely clamp the gripping tool to a length of pipe.

A further object is to provide a novel pipe gripping tool which is easily fastened around the pipe in upright position, and in which the weight of the pipe increases the gripping action.

A still further object is to provide a novel pipe gripping tool which is simple and inexpensive to make, and easy to handle and manipulate.

These and other objects are accomplished by the parts, construction and arrangement of the novel tool comprising the invention, a preferred embodiment of which is shown in the accompanying drawing and set forth in the specification as exemplifying the best known mode of carrying out the invention, the invention being set forth in general terms in the following general statement, and the scope of the invention being defined in the appended claims.

In general terms, the pipe gripping tool of the present invention includes an H-shaped frame having preferably flat side bars connected by a preferably cylindrical crossbar, the suspending cable or chain being attached at its ends to adjacent ends of the side bars for suspending the frame, and the opposite ends of the side bars having attached thereto below the top of the crossbar the ends of a pipe-gripping chain looped over the crossbar and around a length of pipe in upright position between the said adjacent ends of the side bars and against the crossbar.

Referring to the drawing in which a preferred embodiment of the invention is shown by way of example:

2

Figure 1 is an isometric view of the novel pipe gripping tool in operative position, showing in dot-dash lines a length of pipe gripped by the tool;

5 Fig. 2 is a transverse sectional view as on line 2—2, Fig. 1;

Fig. 3 is a fragmentary plan view with the gripping chain removed;

10 Fig. 4 is an enlarged fragmentary elevation looking toward the inside of the rear end of one of the side bars, showing the manner of detachably connecting the suspending chain thereto; and

15 Fig. 5 is a fragmentary sectional view as on line 5—5, Fig. 4.

Similar numerals refer to similar parts throughout the several views of the drawing.

The novel pipe gripping tool is preferably H-shaped and consists of a pair of side bars 6 and 7 which may be made of flat bar stock and are connected intermediate their ends by a crossbar 8 which is preferably cylindrical. The rear ends of the side bars 6 and 7 are preferably connected to the ends of a flexible support which may be a chain 9 connected in usual fashion to the hook of a crane or hoist for suspending the tool. As shown, one end of the chain may be permanently secured to the rear end of a crossbar 6 by means of a yoke 10 having its ends pivotally connected to a pintle 11 extending through the bar.

30 The other end of the chain is detachably connected to the rear end of the side bar 7. Preferably the other end of the chain is connected to a yoke member 12 which has a lower crossbar 13 entered in a slot 14 which extends upwardly from the bottom edge of the side bar 7. When the crossbar 13 is in the enlarged portion 15 of the top of the slot, it is prevented from accidentally falling out of the slot by means of a gravity latch 16 which is pivoted in the side bar 7 adjacent the slot 14, and which has a latch finger 17 at its upper end normally resting on the bottom edge of the enlarged portion 15 of the slot. As shown in dotted lines in Fig. 4, when it is desired to detach the end of the suspending chain 9 from the slot 14 of the side bar 7, the latch 16 is moved upwardly to allow the crossbar portion 13 of the yoke member 12 to drop out of the slot 14.

35 The front end of side bar 6 is preferably provided with an angular bracket 18 extending horizontally inward toward the side bar 7 and located below the crossbar 8. An eye bolt 19 is screwed into the bracket 18 and locked therein by a nut 20, and the upper end of the eye bolt is connected to a link on one end of a pipe-gripping chain 21, the eye of the bolt 19 preferably being located below the top of the crossbar 8.

40 The other end 22 of the chain 21 hangs free, and the chain is of such length as to extend over the top of the crossbar 8 and be looped around a length of pipe L when the pipe is positioned sub-

stantially upright between the rear ends of the side bars 6 and 7, as indicated in dot-dash lines in Figs. 1 and 3.

The front end of the side bar 7 is adapted to engage selectively the links on the free end portion of the chain so as to grip the chain and hold it tightly around the length of pipe L in substantially upright position, in a manner shown in Fig. 1. Preferably, the lower edge of the front end of side bar 7 is provided with a slot 23 which is of such width as to receive and hold a link of the chain 21 in substantially horizontal crosswise position, as indicated by the link 21a. The upper edge of the front end of side bar 7 is preferably provided with a notch 24 which is relatively narrow and is adapted to receive and hold another link 21b in substantially vertical crosswise position. Thus when the free end portion 22 of the chain is wrapped around the front end of side bar 7 with the links 21a and 21b engaged in the slot 23 and notch 24 respectively, the chain will be tightly gripped and held around the pipe L.

In the operation of the novel pipe gripping tool, the tool is suspended with the rear ends of the side bars 6 and 7 straddling a length of pipe L, as shown in Figs. 1 and 3, and the free end of the chain 21 is then looped around behind the pipe and pulled forwardly to remove substantially all of the slack in the loop, whereupon the links 21a and 21b are engaged with the front end of the side bar 7 as previously described. The suspending chain 9 is then raised to lift the pipe, and when the weight of the pipe is applied to the tool, the rear ends of the side bars 6 and 7 will swing upwardly about the crossbar 8 as a pivot, thus taking up any remaining slack in the loop of chain 21 and causing it to grip tightly around the pipe. The rear end of the crossbar 8 may be provided with ribs or beads 25 for engaging spaced points on the pipe surface and increasing the frictional contact between the pipe and the crossbar 8.

The novel pipe gripping tool will grip a length of pipe anywhere between its ends and securely hold it in substantially upright position while being raised or lowered, the weight of the pipe serving to increase the gripping action.

Moreover, the novel tool is quickly and easily fastened or unfastened by unskilled persons without the use of fastening tools, and utilizes a loop of ordinary chain to obtain the positive gripping action.

In the foregoing description, certain terms have been used for brevity, clearness and understanding, but no unnecessary limitations are to be implied therefrom beyond the requirements of the prior art, because such words are used for descriptive purposes herein and are intended to be broadly construed.

Moreover, the embodiment of the improved construction illustrated and described herein is by way of example, and the scope of the present invention is not limited to the exact details of construction.

Having now described the invention, the construction, the operation and use of a preferred embodiment thereof, and the advantageous new and useful results obtained thereby; the new and useful constructions, and reasonable mechanical equivalents thereof obvious to those skilled in the art, are set forth in the appended claims.

I claim:

1. A pipe gripping tool for suspending a length of pipe in substantially upright position, including an H-shaped frame having side bars spaced

for straddling the pipe and connected by a crossbar, a chain having its ends attached to adjacent ends of said side bars for suspending the frame, a pipe gripping chain looped over the crossbar and around a pipe located between said adjacent ends of said side bars and contacting said crossbar, and means on the opposite ends of said side bars for connection with the two ends of said chain loop.

2. A pipe gripping tool for suspending a length of pipe in substantially upright position, including an H-shaped frame having side bars spaced for straddling the pipe and connected by a crossbar, attaching means on adjacent ends of said side bars for connection with the ends of a suspending chain, a pipe gripping chain extending over the crossbar and looped around a pipe located between said adjacent ends of said side bars and against the crossbar, and attaching means on the opposite ends of said side bars below the top of the crossbar for connection with the ends of said chain loop.

3. A pipe gripping tool for suspending a length of pipe in substantially upright position, including an H-shaped frame having side bars spaced for straddling the pipe and connected by a crossbar, means on the rear ends of said side bars for attaching the ends of a flexible support thereto, a bracket on the front end of one of said side bars, a chain attached at one end to said bracket, and means on the front end of the other side bar for detachably holding selectively links of said chain when it is looped over the crossbar and around a pipe in substantially upright position between said rear ends of said side bars and engaging said crossbar.

4. A pipe gripping tool for suspending a length of pipe in substantially upright position, including an H-shaped frame having side bars spaced for straddling the pipe and connected by a crossbar, means on the rear ends of said side bars for attaching the ends of a flexible support thereto, a chain attached at one end to the front end of one side bar, and means on the front end of the other side bar for gripping selectively links of said chain when extending in a loop over the crossbar to grip a pipe in substantially upright position located between said rear ends of said side bars.

5. A pipe gripping tool for suspending a length of pipe in substantially upright position, including an H-shaped frame having side bars connected by a crossbar, a flexible support attached at one end to the rear end of one side bar, latch means detachably connecting the other end of said support with the rear end of the other side bar, a bracket on the front end of one side bar below the top of said crossbar, a chain attached at one end to said bracket, the front end of the other side bar having a slot in its lower edge for engaging selectively one of the links of said chain when it extends in a loop over the crossbar, and the front end of said other side bar having a notch in its upper edge for engaging another link of said chain to grip the chain.
